X-RAY DEVICE

**Louis Frederick Ehrke, Newark, N. J., assignor to
Westinghouse Lamp Company, a Corporation of
Pennsylvania**

Application October 14, 1930. Serial No. 488,592

2 Claims. (Cl. 250—35)

This invention relates to X-ray devices and more particularly to X-ray devices useful in the therapeutic application of X-radiation to living tissues, and still more particularly to a type of X-ray device which may be introduced within body cavities and to means to electrically insulate the device so as to protect the body of the patient from deleterious electric currents during operation of the device and in the event of inadvertent fracture of the device.

In copending application Serial No. 488,008, filed October 11, 1930, which application is assigned to the same assignee as the present invention, I have disclosed an X-ray device suitable for use in internal X-ray therapy, comprising an elongated tubular glass envelope, an anode and a cathode disposed with respect to one end of said envelope such that X-radiation may be drawn off at that end, an interiorly disposed X-ray absorbent shield member enclosing the end of the anode and said cathode arranged to permit the egress of a beam of X-radiation in a predetermined desired direction and means in said envelope in the path of said radiation to facilitate the egress of the rays through the enclosing envelope.

The end of the enclosing tubular envelope housing the cathode and the end of the anode may be of relatively small diameter such as to permit the insertion of the device in an oral or other such cavity of the human or animal body and may be formed as an extension of the main body of the tubular envelope if desired. In the specific structure shown the elongated cathode end of the device may be of any desired length to serve the specific purpose desired.

It is necessary in such a device to provide means to electrically ground the inserted end of the device to substantially earth potential so that the body of the patient should not be exposed to deleterious electrical currents during operation of the device and in the event of inadvertent fracture of the device.

It is one of the objects of this invention to provide means to electrically shield the body of the patient from the electric currents applied to the X-ray device.

It is another object of this invention to provide means to exteriorly sheath the inserted end of such an X-ray device with electrically conducting material pervious to a beam of X-radiation at a predetermined section.

It is another object of this invention to facilitate the therapeutic application of X-radiation within a living body.

These and other objects and advantages of the invention will be apparent as the invention is more fully disclosed.

In accordance with the objects of the present invention I have provided the elongated extended end of the X-ray device of the above identified copending application with a thin electrically conductive sheath member which is adapted to closely contact the exterior surface of the said extended end and which is maintained substantially at ground potential. Means are provided in said shield to permit the egress of the preferred beam of X-radiation in the desired direction.

Before further disclosing the nature and scope of my invention reference should be made to the accompanying drawing wherein

Fig. 1 shows in side elevational view partly in section an X-ray device constructed in accordance with the invention of my above identified copending application with one type of exterior electrical shield member in position.

Fig. 2 is a plan view of the cathode end of the X-ray device illustrating one modification of the X-ray pervious window in the external shield member;

Fig. 3 is a view taken along plane III—III, Fig. 1;

Fig. 4 is an enlarged side elevational view of a second modification of the present invention partly in section;

Fig. 5 illustrates in enlarged side elevational view partly in section, the application of the modification shown in Fig. 4;

Fig. 6 shows a sectional side elevational view of a third modification of the present invention; and

Fig. 7 is an enlarged sectional view of the type of exterior shield employed in the illustration of Fig. 6.

Referring to Fig. 1 the X-ray device illustrated therein has been fully disclosed in my above identified copending application and briefly comprises an enclosing tubular glass envelope 1 having a reentrant stem 2 and an elongated cathode end section 3. An anode 4 is axially supported by means of a collar 5 to spring clip member 6 which frictionally engages the interior surface of the envelope 1. The anode extends axially within the tubular envelope 1 into the extended end portion 3 and in the end thereof is located the customary target capable of emitting X-radiation when subjected to electronic bombardment.

The end of the anode is enclosed by an X-ray impervious shield member 7 adapted to frictionally engage the interior wall of the envelope 1.

and terminating in a focusing cup member 8 within which is positioned a cathode (not shown) electrically connected to leading in wires 9 and 10 extending through the focusing member 8. One of the leading in wires 9 is electrically connected to the focusing cup 8 and the other is electrically insulated therefrom. Means are provided such as an opening 11 in the focusing cup 8 to permit the egress of a beam of X-radiation along substantially the center longitudinal axis of the device, and means 12 comprising a thin glass window is provided to facilitate the passage of the beam of X-radiation through the wall of the enclosing glass envelope. The specific X-ray device may be evacuated or filled with a preferred or desired pressure of an inert monatomic gas, as desired.

When the elongated end of the device is inserted within an opening to the interior of a living body there is a great liability that some obstruction or unexpected event should cause fracture either of the thin glass window 12, or of the glass of the extended end portion 3 which may in some instances be of relatively small cross-sectional diameter. In event of fracture of the glass it would be highly undesirable to permit the scattering of glass fragments within the body opening.

There is also a danger that during operation of the X-ray device or in the event of fracture of the same, that electric currents will be caused to circulate through the body of the patient.

I provide therefor about the exterior of the extended portion 3 an electrically conductive shield member 13 which preferably is comprised of relatively thin sheet metal adapted and arranged to make spring contact with the exterior surface of the glass, in the manner illustrated at 14.

The end of the shield member 13 may totally enclose the end of the extended section 3, if desired, and if of sufficient permeability to X-radiation, or may be arranged as is illustrated in Fig. 1, to overlap the end of the tube and adapted to engage a separate end piece 15 which may be of wire mesh as illustrated or of thin metal sheet permeable to X-radiation.

The other end of the shield member may be extended in the manner illustrated to form a guard 16 to prevent the contact of the body of the patient with leading in conductors 17 and 18. Means 19 are provided to electrically connect the shield member to one of the lead wires 18. An idea of the shape of the guard extension 16 may be gathered from an examination of Fig. 3. A better idea of the clip shield member 13 may be obtained by an examination of Fig. 4. The extended guard feature 16 of Fig. 1 is not shown in Fig. 4 as it is contemplated that a separate and detachable guard member may be employed, if desired.

A modification of the present invention is illustrated in Fig. 5 wherein instead of the spring clip shield member 13 of Fig. 1 it is contemplated that the exterior surface of the extended glass section should be provided with a closely adherent metallic surface as by electrolytic depo-

sition thereon, sprayed metal surface, or a metal surface formed by the thermal decomposition of organic salts in a manner heretofore employed in the prior art. This electrically conductive surface should be grounded to one end 80 of the filament in any convenient manner.

It is contemplated in this arrangement to employ a relatively small end guard shield which may be of the type shown in Fig. 4, or of the type shown in Fig. 7 having a rolled edge 20 85 adapted to engage a recessed portion 21 in the extended end portion of the device in a manner as is illustrated in Fig. 6.

The X-ray previous end shield members 15 may be interchangeable as is illustrated in Figs. 90 1, 6 and 7 or may be unitary with the clip shield member 13 in the manner illustrated in Figs. 4 and 5. For low voltage devices the end shield member should be comprised of metal gauze. For high voltage devices they may be comprised of 95 thin sheet metal such as aluminium.

It is apparent from the above description of the present invention that there may be many modifications and departures made of the specific embodiment herein disclosed without departing 100 essentially from the nature and scope of the same and such modifications and departures are anticipated as may fall within the scope of the accompanying claims.

What is claimed is:

1. An electric discharge device comprising an enclosing dielectric envelope having an anode and a cathode therein, said envelope having an elongated section, said elongated section having a re-entrant bulbous portion integral therewith 110 at one end thereof, a part of said bulbous portion being relatively thin as compared to the corresponding dimension of the remainder of the envelope and a protective covering secured to said elongated section at said end, said covering 115 being out of contact with said relatively thin part of said bulbous portion, said covering being removably secured to said envelope and surrounding said bulbous portion.

2. An X-ray tube comprising a plurality of 120 electrodes, leading-in conductors for said electrodes, an envelope encasing said electrodes and having an elongated section adapted to be inserted in the opening of a living body and to emit 125 X-radiations in a preferred direction from within said elongated section, an electrically conducting shielding means surrounding said elongated section and being closely adjacent a substantial area of said elongated section, a bulbous window 130 integral with and at one end of said elongated section, said bulbous window having a portion thereof relatively thin as compared to the corresponding dimension of the remainder of the envelope and a protective covering cooperating 135 with the end of said elongated section and disposed adjacent said bulbous window to guard said window from fracture, a portion of said shielding means being disposed adjacent said leading-in conductors to guard the same from contacting with said living body when inserted therein. 140
